WILLIAM H. ELBELT AND CHARLES H. BROOKS, OF HURLEY, NEW MEXICO.

CONTROL SYSTEM FOR AIR LIFTS.

Application filed May 15, 1922. Serial No. 561,079.

To all whom it may concern:

Be it known that we, WILLIAM H. ELBELT and CHARLES H. BROOKS, citizens of the United States, residing at Hurley, in the county of Grant and State of New Mexico, have invented a new and useful Control System for Air Lifts, of which the following is a specification.

This invention relates to a system for regulating discharge and maintaining submergence level of one or more air lifts lifting liquids or liquids and solids, such as water, pulp, water and ore, etc. The accompanying drawings illustrate an embodiment of our invention and referring thereto, Fig. 1 is an elevation partly in section of two air lifts connected for control according to this invention, the several parts being shown diagrammatically. Fig. 2 is a vertical section 20 showing the submergence controlling valve.

In the drawings, 1 indicates the well, tube or pipe which is connected at its upper end to a discharge box 2 and is provided at its lower end with a foot piece 3 to which is connected the compressed air supply line or pipe 4 for supplying the air required for the air lift operation. Said air line is connected to receive air from a compressed air tank 5, into which air is compressed by the usual compressor means 6, a valve 7 being included in the line or pipe connection from the said compressed air tank to each well to control the supply of air to such well, said valve being operated automatically as hereinafter set forth.

In the particular application of our invention hereinafter described the air lift is used to lift a mixture of liquids and solids, for example, water and ore, such mixture being supplied to the upper end of the well pit 8 in which the air lift pipe 1 extends so that the mixture of liquids and solids will pass into the bottom of the well pipe and will be raised by the air lift operation to a height greater than that at which it was delivered. Any suitable means may be used for supplying the mixture of liquids and solids, for example water may be supplied through a pipe 9 and ore may be supplied from a bin 10 by feed means 11 and chute or hopper 12, the

pipe 9 and chute 12 discharging into the pit 8. The water and ore may be mixed in the chute or hopper 10 before passing to the pit 8. It is obvious that in thus feeding liquid and solid material into the pit by the usual mechanical devices and in the customary manner, there will be some variation in the rate of feeding such material, and it is therefore advantageous to provide means for maintaining a constant submergence 60 level regardless of such variations. The air compressor 6 is equipped with a standard governor in the usual manner so as to maintain a uniform pressure in the air receiver or tank 5, the compressed air being supplied 65 to such receiver at sufficient volume and pressure to lift the maximum amount of ore and water that may be delivered to any one lift of the system or to all of such lifts.

The length of the well pipes 1 and the 70 depth of the respective piece 8 for the well or wells should be such as to provide the required submergence for lifting the mixture of liquids and solids from the level indicated at *a—a* to the level of discharge indicated 75 at *b—b*. Thus for a lift of 45 feet from *a—a* to *b—b*, the air lift column from the bottom of the foot piece to the top of the well tube should be about 125 feet giving about 65% submergence or 80 feet from the 80 supply level *a—a* to the bottom of the column.

In order to operate efficiently the level of ore and water or submergence level of the pit 8 should always remain as near as possible to the same height, and in order to effect this when operating one or more lifts by one compressor, we provide a regulating device to control the amount of compressed air furnished to the foot piece of these columns, such device controlling the valve 7 as hereinafter set forth.

Valve 7 is provided with a stem 14, which is connected to a diaphragm 15, and a diaphragm chamber 16, the construction being 95 such that the opening in valve 7 is gradually increased when said stem rises and gradually decreased when said stem falls. The diaphragm chamber 15 is connected by a pipe 17 to a submergence chamber or pipe 100

18 closed at its upper end and open at its lower end into the well pit 8 aforesaid, in such manner that the lower end of said chamber is immersed in the liquid (mixture 5 of ore and water) in the well when the air lift is operating at normal submergence. Valve stem 14 is further controlled by means of a lever or arm 19 pivoted at 20 to a fixed support and pivotally connected to such 10 valve stem, said lever being provided with adjustable balance weights 21 and 22 for producing adjustable downward pressure on the valve stem tending to hold the valve closed. Adjustable minimum and maximum 15 opening stops 25 and 24 formed, for example, as stop screws, are provided for the valve arm 19. It will be understood that the operation of the valve 7 by means of the dia- 20 phragm 15 is such that the valve is gradu- ally opened or closed in the movement of the dia- 25 phragm so that the amount of air supply to the air lift apparatus is gradually varied in response to the operation of the dia- phragm by reason of the variation of pressure in chamber 18.

To set the apparatus, valve 7 is opened by lifting arm 19, so that the air lift action is increased, until the level of ore and water is pumped below open end of pipe or cham- 30 ber 18. Valve 7 is then allowed to close sufficiently to permit the ore and water level to be brought back to line $a-a$ (the desired submergence level) and at the same time entrapping a certain amount of air in cham- 35 ber 18 and compressing it, say, to a pressure of about one-half pound per square inch, the minimum opening stop 25 being set to operate a little below this point and prevent valve 7 from closing entirely. Then as the 40 level of water and ore rises in pit 8, the entrapped air will be further compressed, thereby increasing the pressure on dia- phragm 15, and causing valve 7 to operate so as to increase the opening therein, and 45 admit more air to the foot piece of the well. More water and ore will then be lifted, caus- 50 ing the level of liquid in the well pit to return to the line $a-a$. The maximum opening stop 24 may be set at such a point as to limit the opening of valve 7 to a position which will allow sufficient air to pass to handle the largest volume of material which the air lift is required to handle. If the level of liquid in the well pit falls below line 55 $a-a$, a converse action will take place, the resulting decrease of pressure in chamber 18 and on diaphragm 15, causing the valve 7 to more nearly close so as to permit less air 60 to pass to the well, until the level of liquid again rises to the line $a-a$. It is possible, by the above described means, to hold the level of ore and water within limits of say one foot above and below the normal sub- 65 mergence level $a-a$, thereby ensuring efficient operation of the air lifts. The differ-

ent air lifts connected to the same com- 70 pressed air service may operate at different submergence, the respective control valves 7 therefor being adjusted to provide the re- quired submergence for each well. Differ- 75 ent liquids or different mixtures of liquids and solids will require different adjustments of the regulating device. It will be seen that the operation of the above controlling mechanism to maintain the desired sub- 80 mergence is, within reasonable limits, in- dependent of the pressure in the air supply lines. This fact is of great advantage when two or more air lifts are operated from one air supply or compressor, as it enables the supply of air to any one lift to be varied and regulated without varying the main air supply or regulating the compressor, and consequently without affecting the air sup- 85 ply to the other lift or lifts.

What we claim is:

1. In combination with a well having a pit, a well tube extending therein, and pro- 90 vided with air lift means and a compressed air supply line therefor, a valve in said com- pressed air line adapted to gradually vary the supply of air from said line to the air lift means, a submergence chamber opening at its lower end into the well pit in such manner that air is entrapped and compressed in said chamber by liquid in the well pit, and pneumatic operating means for said valve connected to said chamber and op- 95 erated by changes of pressure therein to gradually increase the flow of compressed air through said valve as the submergence of the well increases and to gradually de- 100 crease the flow of compressed air through said valve as the submergence of the well decreases, so as to tend to maintain approx- 105 imately constant submergence.

2. A construction as set forth in claim 1 and comprising, in addition, adjustable means for limiting the opening and closing 110 movements of the valve.

3. In combination with a well having a pit, a well tube extending therein, and pro- 115 vided with air lift means and a compressed air supply line therefor, a valve in said com- pressed air line adapted to gradually vary the supply of air from said line to the air lift means, a submergence chamber opening at its lower end into the well pit near the upper end of said well pit and exterior of 120 said well tube and said air supply line in such manner that air is entrapped and compressed in said chamber by liquid in the well pit only when said liquid is near or above the desired operating level, and pneu- 125 matic operating means for said valve connected to said chamber and adapted to gradually operate said valve so as to in- crease the supply of air to said air lift means as the pressure in said submergence chamber increases, and to gradually operate said 130

valve so as to decrease the supply of air to said air lift means as the pressure in said submergence chamber decreases, so as to maintain approximately constant submergence.

4. A construction as set forth in claim 3, and comprising, in addition, adjustable

means for determining the maximum and minimum opening positions of said valve.

In testimony whereof we have hereunto 10 subscribed our names this first day of May 1922.

WILLIAM H. ELBELT.
CHARLES H. BROOKS.
